KNOCKDOWN BOX

Samuel N. Leopold, Chicago, Ill., assignor to Morris Paper Mills, Morris, Ill., a corporation of Illinois

Application March 18, 1933, Serial No. 661,483

2 Claims. (Cl. 229—41)

The present invention relates to the art of packaging materials, and has particular reference to improvements in the production of packages especially adapted for use in connection with 5 frozen products, such as ice cream, and the like.

A primary object of the invention is to provide an improved method and container for packaging ice cream and similar commodities.

An additional object is to provide an improved 10 ice cream container in connection with which it is not necessary to employ metallic securing or supporting means.

A still further object is to provide a collapsible 15 container which is economical, easily manufactured, and easily erected for use.

These and other objects will be apparent from a consideration of the following and illustrative and explanatory description and by reference to the accompanying drawings, in which

20 Fig. 1 is a cross-sectional view of a container constructed in accordance with my invention and including an outer casing and inner casing;

Fig. 2 is a perspective view of the outer container;

25 Fig. 3 is a perspective view of an insert adapted to be used in connection with the outer casing, and a bottom section which is used with the insert;

Fig. 4 is a fragmentary, sectional view of the 30 outer casing shown in Fig. 2;

Fig. 5 is a plan view of a blank cut and scored so that it may be formed into the outer container shown in Fig. 2;

Fig. 6 is a plan view showing a blank cut and 35 scored so that it may be formed into the inner container or insert shown in Fig. 3;

Fig. 7 is a view of the blank showing partial 40 erection of the blank disclosed in Fig. 5;

Fig. 8 is a perspective view showing a full erection 45 of the blank shown in Fig. 5;

Fig. 9 is a still further disclosure of the method of forming the finished container;

Fig. 10 shows the last step in forming the collapsed container;

45 Fig. 11 discloses the outer container in partially erected position;

Fig. 12 is a perspective view of a container constructed in accordance with my invention and having eight vertical sides; and

50 Fig. 13 is a plan view of a blank from which the outer casing of the container shown in Fig. 12 is constructed.

It has been recognized heretofore that the use 55 of fibre containers for packaging materials such as ice cream is highly advantageous. The me-

tallic cans which were used for this purpose prior to the introduction of fibrous containers, and which are still used to a considerable extent, present a number of problems. As an example, it is necessary that the cans be returned from the dispenser of the ice cream to the producer of the same. Also, a complete sterilization is required before the containers may be subsequently used.

The fibre containers which have met with considerable success in packaging frozen materials, such as ice cream, are generally formed of a single thickness cylinder having on its bottom section a metallic ring or binding portion which serves to form a base for the container, maintaining it in predetermined shape and position 10 and providing a suitable base on which to rest the carton, which base will not be deleteriously affected by casual moisture or by conditions met in handling during packing, freezing and shipping.

In accordance with the present invention there is provided a container for frozen materials of the class described which is collapsible into flattened condition and in connection with which it is not necessary to employ auxiliary base members such as metallic rings and the like. The container is of such structure that it may be formed economically and rapidly.

As shown in Figs. 1 and 2 of the drawings my container includes a continuous outer body section 10 of polygonal shape and including a bottom section 11 and a non-continuous inner body section or liner 12 adapted to assume a similar shape upon insertion of a detached bottom or disk 13.

To form the outer container a single blank of material may be cut and scored in the manner shown in Fig. 7, for example. That is, a blank of cardboard or other suitable fibrous material is cut to form opposite or complementary side sections 14, each of which is scored to form a plurality of individual side sections 15, 16 and 17, the sections 15 and 17 constituting outer wings or side sections while the sections 16 form intermediate side sections. To the outer edges of one 45 of the sections 15 and one of the sections 17 are secured attaching wings or portions 18 and 19 respectively. In the embodiment shown in the drawings these wings are both attached to one side of the blank, while it is quite possible that one or both of the attaching portions could be secured along the corresponding edge or edges of the opposite side of the blank. The side sections 14 are spaced apart and united together by means of an integral bottom section 11. This 55

bottom section, which constitutes the base for the container, is of polygonal shape and has integrally connected thereto along its free edges a plurality of flaps 20, the function of which will be described more specifically hereinafter. That is, between sections 15 and along the free edges of the polygonal bottom section 11 are provided flaps which are connected to the bottom section along a score line, the two flaps between sections 15 being separate and independently movable. Similarly, between the sections 17 are provided two independently foldable flaps 20.

The outer container 10 shown particularly in Figs. 1 and 2 is of hexagonal shape and the bottom section 11 is similarly formed with six sides. As shown in Fig. 7 the complementary side sections 14 are integrally connected with opposite and parallel sides of the bottom section, a score line defining the point of jointure. In addition, the bottom section 11 is provided with a score line 21 which divides the bottom section in half along a line parallel to those edges of the bottom section to which the side sections 14 are attached. It will be seen that the score line 21 terminates at the point of meeting of the free edges of the bottom section, and more particularly between the independently movable flaps 20.

Figs. 7 to 11 disclose the method by which the outer container 10 is formed from the blank shown in Fig. 5. A first step in the operation of assembling or forming the outer container consists of folding the independently movable flaps 20 into substantially erect position as shown in Fig. 7. As a second stage in the operation, the bottom section 11 is folded along the central score line 21, the side sections 14 being moved toward each other and the bottom section being raised into substantially inverted V-shape and then into parallel contiguous relation. The complementary side sections 14 are then folded over in the manner of closing a book into parallel and contiguous relation in the manner shown in Fig. 9. When the complementary side sections 14 are folded together each of the attaching flaps 19 is bent over against the outer face of its opposed side section and secured thereto as shown in Fig. 10. The attaching portions may be stitched to the corresponding side section or they may be stapled or otherwise attached thereto by well-known means, as will be understood by those skilled in the art, thereby completing the formation of the outer container.

The completed outer container shown in Fig. 10 is in the collapsed or flattened condition in which it is desirable to ship it to the user. In this condition the bottom section 11 is folded upwardly within the container and the flaps 20 are folded inwardly against the face of the bottom section. When it is desired to erect the outer container from collapsed position, it is merely necessary to press the outer edges of the flattened container inwardly, thereby distending the wall sections 15, 16 and 17. As the flattened container is pressed inwardly along the outer edges of sections 15 and 17 the bottom section spreads toward flattened condition as will be seen in Fig. 11, the erection of the outer container being complete when the bottom section assumes a substantially horizontal position. In this position the bottom edge of the walls 15 are in proximity to two of the free edges of the bottom section 11, while the lower edge of individual side sections 17 are in proximity to the opposite free edges of the bottom section 11.

The natural resilient character of the fibrous

material employed causes the free flaps 20 to rotate toward vertical position upon erection of the outer container, and these free flaps ordinarily will seat against the side sections 15 and 17, as shown in Fig. 4.

In connection with the erected outer container 10 an inner container or liner 12 is employed, the structure of which is shown in Figs. 1, 3 and 6. As will be seen from Fig. 6 the inner container or liner may be formed from a single blank of material by cutting and scoring the blank to form a plurality of wall sections 22 equal in number to the number of wall sections in the outer container, for this example, six. To the free side edges of the outer wall sections 22 are secured overlapping portions 23. To the lower edges of the wall sections 22 are attached a number of independently inwardly foldable bottom supporting flaps 24. The liner is simply assembled by bringing the portions 23 into overlapping relation as shown in Fig. 3. The insert is then placed into the outer container and pressed downwardly until the flaps 24 assume a horizontal position against the bottom 11 of the outer container, as shown in Fig. 1. The lower portion of the inner container or liner will lie inside the upturned flaps 20 of the bottom section.

To complete the assembly of the container, an inner and separate bottom or disk 13 of shape similar to that of a cross-section of the outer container when erected, is inserted edgewise into the inner liner 12, and one side edge of the bottom is placed against the lower edge of one of the walls 22 between such wall and its flap 24. The disk is then pressed down into the assembled position shown in Fig. 1. In order to lock the container in erect or set-up condition it is preferred to employ a disk 13 which is slightly oversize whereby, when pressed into the position shown in Fig. 1, this disk expands the lower portion of the liner 12 sufficiently to form a tight connection therewith. The container is then ready for use in the usual manner. For instance, it may be loaded with liquid or semi-frozen ice cream and the freezing operation thereafter carried on to completion. As the liquid or semi-frozen contents are introduced, the free upper end of the container tends toward distortion out of its uniform polygonal shape. That is, the container will tend to form a cylinder under the outward pressure of the contents. Expansion of the contents upon freezing accentuates this tendency. In order to provide for an even distortion of the package from its polygonal shape, and thus to provide for uniformity as to quantity in filling successive containers, it is preferred to provide a series of longitudinal score lines 25 along the individual side walls of the outer container, these score lines terminating at a distance spaced from the bottom of the container. The inner liner is provided with longitudinal score lines 26 along the side walls 22 thereof. As the container is filled, the inner liner and the outer container will be uniformly and evenly distorted whereby the predetermined volume for a given height of the container will be accommodated. By terminating the score lines at a point spaced above the bottom of the container the bottom of the container is not distorted out of its polygonal shape. Thus in the finished product the bottom of the container will be substantially hexagonal in cross-section and the container will approach, towards the top thereof, a cylindrical shape.

Ordinarily it will be desirable to provide some means for closing the top of the container, but

this may be done in any conventional manner, and does not constitute a part of the present invention. Many satisfactory types of closing devices are available and the particular one selected 5 will depend upon such factors as cost and strength of materials.

After the ice cream or other material has been placed in the container and as the freezing is completed, the expansion of the contents will cause the latter to form with the container a more or less unitary body. That is to say, the ice cream will hold to the walls of the container. Thereby the bottom of the container is relieved of a considerable portion of the weight of the ice cream. This action is materially assisted by the 10 tendency of the upper portion of the container to expand into cylindrical shape upon the freezing of the ice cream.

As shown in the drawings, the free edges of the inner liner are not secured together in a permanent manner. It is sufficient that there be an overlap of these free edges, as shown in Fig. 3. This enables the user to assemble the insert with the outer container rapidly and easily. That is, 20 the free edges of the insert may be overlapped to such extent that portions of the outer wall sections 22 are in overlapped condition, thereby making the preliminary size of the insert considerably smaller than the fixed size of the outer container. Thus the insert may be dropped 25 into the container and subsequently expanded to its ultimate size.

In the assembled container the upwardly extending flaps 20, which are between the outer container and the insert, form a jointure between the free edges of the bottom section and the free edges of the vertical walls of the outer container. By expanding the insert upon insertion of the inner bottom section 13 a tight fit is had between these upwardly extending flaps 40 20 and the outer container on the one side thereof and the inner container on the other side thereof. In addition, the inwardly extending horizontal flaps 24 are connected to the insert and as weight 45 is placed upon the inner or auxiliary bottom-section 13 a considerable portion of this weight is carried by the flaps 24 in the inner insert. It will be found that the complete container is quite suitable for its intended purpose and is free from points of weakness which are apt to cause deterioration of the carton during use and to permit leakage of the contents. Its strength and stability are obtained without the use of metallic bands or other supporting structures on the bottom of the container.

In the embodiment shown in Figs. 12 and 13 I have provided an octagonal container which is the same in principle but differs from the container described hereinbefore by the provision of two additional sides. The inner container or 50 insert 27 of this embodiment may be formed in the same manner as shown in connection with

the inner insert of the hexagonal container. However, in the outer container 28 one side of the blank 29 is formed with five side sections 30, the intermediate of which is secured to a bottom section 31. The opposite side of the octagonal 5 bottom section 31 has integrally connected therewith the intermediate of three wall sections 32. A plurality of independently foldable flaps 33 are secured to the free edges of the bottom section 31, and a score line 34 is provided through 10 the center of the bottom section 31 parallel to the edges of the bottom section along which the intermediate walls 30 and 32 are connected. As the bottom section is folded upwardly along line 34 upon formation of the carton, as specified 15 hereinbefore in connection with the hexagonal carton, it is desirable to cut the central flaps 33 along a line forming the continuation of the score line 34. The container is then completed as described hereinbefore, an octagonal auxiliary or 20 inner bottom disk being employed to lock the container in erect condition.

Various modifications of the structures described herein will occur to one skilled in the art. For example, in many instances it may be desirable to employ a metallic band along the top of the container in order to insure an even expansion of the materials therein. This band may be of circular shape. Also the bottom and side sections of the outer container may be formed 25 from separate blanks and secured together in a suitable manner. All such modifications and embodiments as come within the spirit of my invention are intended to be included in the appended claims. 35

I claim:

1. A container, comprising an outer body section, a polygonal bottom section connected to said outer body section along opposite parallel edges and having free flap portions adapted to 40 line adjacent said body section, said bottom section having a diametric score line parallel to said opposite edges, an inner body section having inwardly extending flaps connected thereto and an oversize inner bottom section positioned adjacent 45 said flaps and pressed into engagement with said inner body section.

2. A container, comprising a polygonal outer body section, an outer bottom section connected to said body section along opposite parallel edges, 50 said outer bottom section having a diametric score line parallel to said opposite edges, and upwardly extending flaps along its free edges forming a jointure with said body section, an inner container of similar shape to said outer container 55 and having a plurality of inwardly extending flaps resting adjacent said outer bottom section, an oversize inner bottom section positioned upon said inwardly extending flaps and pressed into engagement with said inner container. 60

SAMUEL N. LEOPOLD.
